US0D1047998S

(12) **United States Design Patent** (10) **Patent No.:** **US D1,047,998 S**
(45) **Date of Patent:** **** Oct. 22, 2024**

(54) **LAPTOP**

(71) Applicant: **Intel Corporation**, Santa Clara, CA (US)

(72) Inventors: **Mikko Makinen**, San Jose, CA (US); **Gustavo Fricke**, San Jose, CA (US)

(73) Assignee: **Intel Corporation**, Santa Clara, CA (US)

(**) Term: **15 Years**

(21) Appl. No.: **29/845,962**

(22) Filed: **Jul. 12, 2022**
